DESIGN FOR A TOASTER OR SIMILAR ARTICLE

George W. Walker, Pleasant Ridge, and Kenneth A. Hopkins, Pontiac, Mich.

Application September 1, 1945, Serial No. 121,790

Term of patent 14 years

(Cl. D81—10)

To all whom it may concern:

Be it known that George W. Walker and Kenneth A. Hopkins, citizens of the United States of America and residents of Pleasant Ridge and Pontiac, respectively, in the county of Oakland and State of Michigan, have invented a certain new, original, and ornamental Design for a Toaster or Similar Article, of which the following is a specification, reference being had to the accompanying drawings forming a part thereof and wherein:

Fig. 1 is a perspective view of a toaster or similar article showing our new design;

Fig. 2 is a similar view with the door thereof arranged in open position;

Fig. 3 is a perspective view of the other side of the toaster; and

Fig. 4 is an end elevational view thereof.

The essential features of our design reside in the parts shown in full lines.

We claim:

The ornamental design for a toaster or similar article, as shown and described.

GEORGE W. WALKER.
KENNETH A. HOPKINS.
